(57) **CLAIM**

The ornamental design for a worksurface assembly, as shown and described.

DESCRIPTION

In a preferred embodiment, the nature of this product is a worksurface assembly that is part of a modular office furniture system.

FIG. 1 is a top, front, left perspective view of a first embodiment of a worksurface assembly embodying our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top, front, left perspective view of a second embodiment of a worksurface assembly embodying our new design, the bottom plan view being identical to FIG. 7;

FIG. 9 is a front elevational view thereof;

FIG. 10 is a rear elevational view thereof;

FIG. 11 is a left side elevational view thereof;

FIG. 12 is a right side elevational view thereof; and,

FIG. 13 is a top plan view thereof.

The broken line representations of vertical panel structure in FIGS. 1, 2, 3, 4, 5, 7, 8, 9, 10, 11, and 12 of cabinet structure in FIGS. 1, 2, 3, 4, 5, 7, 8, 9, 10, 11, and 12, of cabinet doors in FIGS. 1, 2, 8, and 9, of cabinet pulls in FIGS. 1, 2, 8, and 9, and of vertical worksurface supports in FIGS. 1, 2, 3, 4, 5, 7, 8, 9, 10, 11, and 12 are for the purpose of illustration only, and form no part of the claimed design.
